DESIGN FOR A CARPET-PATTERN.

Specification forming part of Design No. 5,708, dated March 26, 1872.

To all whom it may concern:

Be it known that I, ALBERT COWELL, of Kidderminster, in the county of Worcester, in England, have invented a new and original Design for Carpets; and I do hereby declare that the following is a full, clear, and exact description thereof, which will enable others skilled in the art to make and use the same, reference being had to the accompanying photographic illustration forming part of the specification.

This invention refers to the new design of the main figure in a carpet, the same being of a rectangular outline with a semicircular prom-

inence in the middle of each line, and surrounded by a border of similar outline. The interior of this figure, its border, and the aforementioned semicircular protuberances are all decorated, as shown. The invention refers, also, to the new ornamental border of the smaller oval figures shown in the design.

I claim as my invention—
